UNITED STATES PATENT OFFICE.

WILLIAM S. NEWCOMET OF PHILADELPHIA, PENNSYLVANIA.

COMBINED VIBRATOR AND TIMER.

No. 923,566.

Specification of Letters Patent.

Patented June 1, 1909.

Application filed August 24, 1903. Serial No. 449,804.

To all whom it may concern:

Be it known that I, WILLIAM S. NEWCOMET, a citizen of the United States, residing in the city and county of Philadelphia, 5 State of Pennsylvania, have invented a new and useful Combined Vibrator and Timer, of which the following is a specification:

This invention relates to a combined vibrator and timer adapted for use in connection 10 with a spark coil apparatus of the type used in connection with gas engines and has for an object to provide a contact which is constant at all speeds of the engine and one which is mechanically operated and does not depend 15 upon the magnetism in the core of the coil for any portion of its operation.

It has for a further object to provide a contact which operates entirely separate from the engine and the circuit in which it is located 20 is always broken when the engine is at rest and furthermore cannot be closed should the engine run backward.

For the purpose of illustrating my invention, I have shown in the accompanying 25 drawings one form thereof which is at present preferred by me, since the same has been found in practice to give satisfactory and reliable results, although it is to be understood that the various instrumentalities of 30 which my invention consists can be variously arranged and organized and that my invention is not limited to the precise arrangement and organization of these instrumentalities as herein shown and described.

Figure 1 represents a side elevation of an apparatus embodying my invention. Fig. 2 represents a section on line $x-x$, Fig. 1. Fig. 3 represents the apparatus in contact position. Fig. 4 represents a diagrammatic 40 view of the connections. Fig. 5 represents a section through one of the contact members.

Similar numerals of reference indicate corresponding parts in the figures.

Referring to the drawings:—1 designates a 45 casing loosely mounted on a shaft 2 adapted to rotate relatively thereto and having fixedly secured thereon a hub 3 the periphery of which is as here shown, divided into suitable sections by a ring of insulation 4 whereby 50 short circuiting between a cam 5 and a trip cam 6 is effectually prevented. The functions of the cam 5 and trip member 6 will presently be described. It will be noted that the ring of insulation 4 preferably forms a 55 part of a member 4' of insulating material separating the outer rim of the hub 3 from

the inner rim and to which it is attached by suitable means.

7 designates a flexible spring contact mounted at a suitable point on the casing 1, 60 in the present instance, being secured thereto by means of an angle strip 8 which is fastened by screws 9 to the casing 1 or other well known means and carrying on the extended angle portion 10 an adjusting screw 11 on 65 which is located beneath the flexible spring 7 is a strip of insulation 12 serving to prevent a current becoming short circuited through the casing proper. Adjusting nuts 13 are provided on the screw 11 which serve 70 the purpose of a binding screw for the connection of a suitable circuit wire. It will be noted that as here shown the angle strip 8 is mounted exterior of the casing and therefore an opening 14 is provided to allow the flexible contact strip 7 to pass into proper position within the casing 1 although it will be readily seen that the same is capable of various arrangements.

At a suitable point on the surface of the 80 strip 7 a contact 15, preferably of platinum, is provided and in the present instance is located near the extremity of the strip in order that the full value of the inertia of the spring member may be brought into play. 16 designates a contact of similar material located in direct alinement with the contact 15, the same being supported preferably on an adjusting screw 17 mounted on a member 18. This member 18, in the present instance, is 85 pivotally mounted on the casing 1 by means of a stud bolt 19 so that it may be swung away from the normal position adjacent the flexible contact 7 as occasion demands. It will be noted that the contact screw 17 is at 90 all points well insulated from the pivoted member 18 but passes directly through in contact with a supplemental contact 20 which latter is provided with a depending portion 21 adapted to engage a contact 22 100 formed on the end of a binding post 23 passing through the casing 1 and to which another wire of the circuit is connected. This binding post 23 is of course surrounded with insulation 24 to prevent contact with the casing 105 itself and consequent short circuiting.

25 designates a trip finger pivotally secured to the member 18 by suitable means as the screw 26 and is provided with outwardly extending ends 27 and 28 to the former of 110 which a spring 29, joined to the casing 1, is connected to maintain the end 28 in the path

of the cam member 5 with which the end 28 co-operates. In order to prevent the spring 29 from drawing the trip finger out of operative position a stop 30 is fixedly mounted on the member 18 and projects a sufficient distance to be engaged by the trip finger 25 and prevent inoperative retraction of that member.

31 and 32 designate wires connecting the mechanism to the proper circuit which as here shown is a primary one of a spark coil 33 of which 34 is the secondary coil and 35 the battery in the primary circuit. It will be clear that each time the flexible strip 7 engages with the contact 16 that a current will be sent through the primary coil which induces a current in the secondary coil 34 in which latter current a spark plug 35 is located by means of which a spark is produced for the purpose of igniting a charge in a gas engine or similar structure.

In operation the shaft 2 is rotated by the engine and the cam 5 is at intervals brought into engagement with the end 28 of the trip finger 25 which it shifts against the tension of the spring 29 and thereby maintains the swinging member 18 stationary and held into engagement with the contact 22 and in position for closing the circuit by means of the flexible strip 7. Just before the cam 5 releases the trip finger 25 the trip cam 6 engages the flexible member 7 and as it passes thereunder withdraws the same some little distance from its position adjacent the contact 16 and as the movement continues the flexible member 7 snaps off of the trip 6 and quickly returns the flexibility thereof allowing the same to react a sufficient distance beyond the normal position to contact with the end of the screw 17 and thus momentarily close the circuit through the primary coil. As soon as this circuit is closed by this contact the cam 5 passes out of engagement with the trip finger 25 and the spring 29 immediately returns the latter to normal position. It will thus be clear that no matter what speed of the engine the interval of contact will always be the same since there is no opportunity for the flexible member 7 to vibrate sufficiently to cause a second contact and also no danger of too short a contact, since the member 18 is always held in position by the cam 5 until the flexible member 7 makes a single contact.

It will of course be understood that by means of my novel mechanism as many contact members as desired may be located within the casing 1 but in the present instance I have shown two, the same being adapted for use in a two cylinder engine one of course for each cylinder, although if an engine of three or four cylinders were used there would be a corresponding number of contacts.

An important feature in my novel con-

struction resides in mounting one of the contacts within the casing so that it may be swung back out of normal position in case the engine should for any reason be started in the reverse direction so that there is no danger of the circuit being closed to produce a spark which would result in the continued rotation of the engine in this direction. It is well known that in certain analogous structures it frequently happens that an explosion takes place in the cylinder at the wrong time and produces a movement of the engine in the reverse direction and in view of the arrangement of the timer contacts, and the like, ignition takes place in exactly the same manner as when the engine is running in a forward direction. By means of the combination herein set forth, should the engine by any means start in a reverse direction the cam 5 will engage with the trip finger 25 and carry the member 18 about the pivot 19 away from the contact making strip 7 thus avoiding any possibility of the circuit being closed to make a positive and continued series of sparks resulting in a constant running of the engine in a reverse direction. The cams 5 and 6 are so located relative to each other that on a reverse movement, that is, to turn them in a clockwise direction, as shown in Fig. 1, the cam 5 has sufficient time in which to engage the arm 25 and shift its movable contact just before it is possible for the flexible member to contact therewith. Of course it will be clear that this lead of one cam over the other must equal or be greater than the distance from the end of the contact 16 to the extremity of the arm 25 and it will of course be noted that even should the cam 6 engage the flexible member 15 at the same time that the cam 5 is in engagement with the movable arm 25, there will still be a movement together before the spring member 15 contacts with contact 16 and during this interval the pivoted member 18 has been shifted to avoid making contact at this time. A further feature relative to this pivoted contact member is the certain breaking of the circuit whenever the engine comes to rest, that is, it is impossible for the engine to stop with the contact mechanism closed so as to maintain the spark coil energized which not only results in a loss of current but in the premature starting of the engine should there be a correct mixture within the cylinder.

It will now be apparent that I have devised a novel and useful construction which embodies the features of advantage enumerated as desirable in the statement of the invention and the above description and while I have in the present instance shown and described the preferred embodiment thereof which has been found in practice to give satisfactory and reliable results, it is to be understood that the same is susceptible

of modification in various particulars without departing from the spirit or scope of the invention or sacrificing any of its advantages.

5 Having thus described my invention, what I claim as new and desire to secure by Letters Patent, is:—

1. In a device of the character described, a casing, a rotatable member therein, a plurality of movable contacts adjacent thereto, means moving with said rotatable member to maintain one contact stationary and means moving with said rotatable member to shift the other contact.

15 2. In a device of the character described, a casing, a rotatable member therein, a plurality of movable contacts adjacent thereto, means moving with said rotatable member to shift one contact and maintain the other contact stationary.

20 3. In a device of the character described, a casing, a rotatable member therein, a flexible contact adjacent thereto, a contact pivoted to said casing, means to shift said flexible contact, and means to maintain said pivoted contact stationary.

4. In a device of the character described, a casing, a rotatable member therein, a flexible contact adjacent thereto, a contact pivoted to said casing, and means on said rotatable member to shift said flexible contact and maintain said pivoted contact stationary.

30 5. In a device of the character described, a casing, a rotatable member therein, a plurality of movable contacts adjacent thereto, a cam on said rotatable member to shift one contact and means moving with said rotatable member to maintain the other contact stationary.

35 6. In a device of the character described, a casing, a rotatable member therein, a plurality of movable contacts adjacent thereto, a cam on said rotatable member to shift one contact, and means insulated therefrom and moving with said rotatable member to maintain the other contact stationary.
